CUTTING MECHANISM

Curtis S. Crafts, Oak Park, Ill., assignor to Goss
Printing Press Company, Chicago, Ill., a corpo-
ration of Illinois

Application June 19, 1933, Serial No. 676,411

18 Claims. (Cl. 164—67)

The present invention relates to folding mechanisms and more particularly to a novel and improved shear cutter and folding mechanism for use with printing presses.

5 Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

15 The accompanying drawings, referred to herein and constituting a part hereof, illustrate one embodiment of the invention, and together with the description, serve to explain the principles of the invention.

20 Of the drawings:

Figure 1 is a vertical section taken on the line 1—1 of Figures 2, 3, 4 and 5, with certain parts omitted, and shows an illustrative embodiment of the present invention. In this figure, certain portions have been broken away, and those portions of the shear-cutter blades lying to the rear of the section plane have been omitted for the sake of clearness;

Figure 2 of the drawings is a fragmentary sectional view looking to the left of the line 2—2 of Figure 1 and shows the left-hand cylinder, with certain parts shown in section;

Figure 3 is a similar view, looking to the right of the line 2—2 of Figure 1, and shows the right-hand cylinder;

Figure 4 of the drawings is a fragmentary top plan view of the left-hand cylinder of Figure 1, with certain parts shown in section;

Figure 5 of the drawings is a similar view of the right-hand cylinder of Figure 1;

Figures 6 and 7 are diagrammatic side elevations of the right-hand cylinder and web, at the beginning and at the end of the cutting operation respectively;

Figure 8 is a diagrammatic end view of the cutting cylinder and cooperating folding cylinder; and,

Figure 9 is a fragmentary, diagrammatic, sectional view of the shear-cutter blades, web and sheet during cutting, showing several successive positions of the blades, web and sheet.

The present invention provides a novel and improved shear cutter and cooperating folding mechanism, in which the folding cylinder and cutter blades cooperate in a novel manner to

prevent buckling of the adjacent ends of the sheet and web at the line of cut. The invention also provides an improved shear cutter mechanism and method of cutting particularly adapted for cutting paper web into sheets at relatively high speeds. A further object is the provision of a shear cutter in which the adjacent ends of paper at the cut are gradually moved away from each other and from both the shear cutter blades immediately after the cutting operation thereby preventing interference of the blades and the cut edges of the sheet and web. The invention also provides an improved construction of shear cutter in which the blades may be set in position easily and with a high degree of precision. 15 Still another object is the provision of a shear cutter mechanism in which the blades clear each other at any point along the blades immediately after completion of the cut at that point.

In accordance with the illustrative embodiment of the invention, the shear cutter comprises a pair of cylinders geared together and provided with cooperating shear cutter blades adapted to cut a web of paper transversely thereof, the cut beginning at one edge of the web and progressing 25 transversely of the web until a sheet is completely severed from the web. As embodied, the leading shear cutter blade projects slightly beyond the pitch circle of its cylinder driving gear, while the following blade is set on the pitch circle of 30 its cylinder driving gear, so that the cutting edge of the leading blade has a slightly faster peripheral speed than either the web or the cutting edge of the following blade. The face of the following blade is set to extend rearwardly inwardly 35 from the cylinder radius, while the leading blade is set on an extension of the following blade face at the instant of cutting at that point. The cylinders, as usual in shear cutters, are rotatably mounted with their axes at a slight angle to the 40 horizontal, and the cutter blades are set with their cutting edges lying substantially on a helix generated about their respective cylinder axes, so that the development of the cutting edges on the web to be cut is at right angles to the path of 45 the web. In order to compensate for the slightly faster travel of the cutting edge of the leading blade, the helices are of slightly greater pitch than usual, with the leading end of each blade at the upper end of each cylinder set slightly in 50 advance of its true helical position.

The cooperating folding cylinder is provided with sheet taking devices, such as grippers, to take the lead end of the sheet as it is cut from the web, and is also provided with the usual folding blades 55

- or knives to fold the sheet. Between each sheet taking device or gripper and its immediately following folding blade or knife, the cylinder surface is formed on a spiral of slightly increasing 5 radius so that the sheet is accelerated slightly immediately after cutting to move its trailing end away from the following shear cutter blade by the spiraled surface of the folding cylinder, the acceleration of the sheet being more than sufficient 10 to compensate for the excess in speed of the cutting edges of both blades over web speed, while the leading end of the web (immediately adjacent to the trailing end of the sheet and formed by the cutting operation) moves relatively away from 15 the cutting edge of the leading blade by reason of the excess speed of the leading blade.

The present embodiment of the invention also includes novel means for accurately positioning the shear cutter blades to insure that all points 20 on the blade lie at the same distance from the cylinder axis, and also provide novel means for testing the accurate positioning of the cutting edges so as to facilitate the proper setting of the blades.

25 It will be understood that the foregoing general description and the following detailed description as well, are exemplary and explanatory of the invention but are not restrictive thereof.

Referring now in detail to the illustrative embodiment of the invention as shown in the accompanying drawings, cutting cylinders 10 and 11 are mounted above the folding cylinder 12 and are adapted to sever the web into successive sheets which are folded and/or collected prior to being 35 delivered.

The cutting cylinders 10 and 11 are preferably of substantially the same size and rotate on axes parallel to each other and inclined slightly transversely of the web, as is usual with shear cutters.

40 Each of these cylinders is provided with a pair of shear-cutter blades having substantially helical cutting edges, each blade being adapted to cooperate with its mate on the other cylinder. Each helical blade starts at the high end of its cylinder 45 and continues around and to the other end of the cylinder, so that as the cylinders are rotated with the web between them, the web is cut along a straight line, transversely of the web.

The right hand cylinder, shown at the right of 50 Fig. 1 and in Figures 3 and 5, comprises a heavy, solid central portion 15 symmetrical with reference to the axis of rotation of the cylinder, and provided with diametrically opposed, substantially radially-extending ledges 16 to which the cutter blades 17 are secured. Cylinder 10 is 55 adapted to rotate in a counter-clockwise direction, and the following side of each ledge 16 is so positioned that the following side of blade 17 is radial with respect to the cylinder axis. The following side of each ledge 16 is a plane, skew with respect to the axis of the cylinder, and set at such an angle that the intersection of the following edge of blade 17 with a cylinder forms the helix required for the cutting edge of the corresponding blade 17.

Blades 17 are preferably formed straight and flat, and are provided with slots 18 through which bolts 19 may be passed to securely fasten the blade to ledge 16. The ends of blades 17 are milled down to provide lugs 20 by which the ends of the blade are securely anchored to the body 15 by clamps 21 near the ends of the cylinder.

70 Means are provided for warping the cutting edges of blades 17 out of a straight line position 75 after they have been secured to the ledges 16, so

as to bend the cutting edge into the desired helix, and for this purpose there are provided a series of uniformly spaced screws 22 threaded into and extending radially of the cylinder body 15 and adapted to push against the rear edge of blade 17. 5 At the ends of the blade the cutting edge normally lies on the desired helix, and the intermediate portions of the blade are warped into the helix by screwing out the screws 22 to the necessary extent.

10 For facilitating the proper setting of the cutter blades and to insure that all points on the cutting edge of the blade are equidistant from the cylinder axis, means are provided for accurately and quickly gauging the blade. As embodied, 15 discs 23 are formed at the ends of the cylinder, coaxial therewith and beyond the ends of the blades 17. These discs are of the proper diameter to form an accurate support for a straight-edge which may be laid on them to extend from 20 one end of the cylinder to the other. By moving the straight edge circumferentially of the cylinder, the position of all points along the edge of the blade may be accurately tested, and the blade may be brought to a true helical shape by moving 25 screws 22 in or out as necessary, after loosening screws 19.

The pitch of the helical cutting edges of the blades 17 is such that, taking into consideration the inclination of the cylinder axis, the development 30 of the helix on the surface of the paper web to be cut is substantially at right angles to the feed of the web. In practice, however, and for reasons later explained it is found preferable to form the ledge surfaces so that the leading ends 35 of the helical blades are very slightly in advance of the true helix, the development of which would be exactly at right angles to the movement of the web.

Means are provided for forming a cylindrical 40 surface on the exterior of the cylinder to reduce disturbing air currents, and for this purpose there are provided two substantially semi-cylindrical shells 25, extending circumferentially from one blade 17 to the other, and from near one end of 45 the cylinder to near the other end. These shells may be supported in any desired manner, but as embodied are supported on the body portion 15 and are secured thereto by screws 26 cooperating with the dovetailed nuts 27, which are slid- 50 able in grooves 28.

Cylinder 11 is of the same general construction as cylinder 10 and is shown at the left of Figure 1, and in Figures 2 and 4. This cylinder is adapted to rotate oppositely to cylinder 10, and is likewise provided with a pair of shear cutter blades 30 of the same general construction as those on cylinder 10, and adapted to make cutting contact with blades 17, point-by-point as the cylinders are rotated in timed relation with each other 60 by gears 31. Shear-cutter blades 30 are mounted on ledges 32 formed integrally with the central portion 33 of cylinder 11, and are secured thereto by means of nuts 34 which clamp the blade against shoulder 38' on bolt 35 threaded into 65 ledge 32. By turning bolt 35 the blade may be raised or lowered on its ledge and may be locked in position by lock nut 39'. The blade supporting surfaces of ledges 32 are also flat and each extends in a single plane from near one end of 70 the cylinder to the other, and are skew with reference to the axis of the cylinder.

As with cylinder 10, a plurality of screws 37 are positioned against the back edge of the shear-cutter blades and are threaded into the cylinder 75

body, serving to warp the cutting edge blade into a true helix with its cutting edge concentric with the cylinder axis, while the ends 38 of the blade are held fast to the cylinder by means of clamps 39 which engage the reduced blade ends.

Gauging means are provided for a facilitating the setting of the blade edge into a true helical path, and comprise a pair of discs 40 of equal diameter formed integrally with the cylinder near its ends and upon which may be supported a straight edge for truing the blades as previously described.

Blades 30, like blades 17 are set with their leading end at the upper end of the cylinder slightly in advance of the true helix, the development of which would lie at right angles to the web path, and the advance is the same for the blades on both cylinders, thereby insuring proper cutting contact of the blades throughout their entire length.

As previously described the following faces of blades 17 on cylinder 10 are preferably radial of cylinder 10, and each point of the leading faces of blades 30 on cylinder 11 is preferably positioned so that each portion of the blade, while cutting, lies on a geometrical projection of the following face of the active blade 17 and radially of cylinder 10, as shown in Figure 8.

Means are also provided for forming a substantially cylindrical surface between the shear-cutter blades 30, and for this purpose substantially semi-cylindrical shells 41 are supported on the cylinder body and are secured thereto by means of bolts 42. When it is desired to vary the setting of the blades 30 or to replace them, these shells may be easily removed affording easy access to the blade mounting and adjusting screws.

Means are provided for driving cylinders 10 and 11 at the same angular speed, with shells 25 and 41 at a peripheral speed substantially the same as that of the paper web to be cut into sheets. For this purpose, the discs 23 and 40 at the ends of the cylinders 10 and 11 support the driving gears 31. At each end, the gears mesh with those of the other cylinder to maintain uniform the angular speeds of the two cylinders as well as to eliminate backlash and maintain the blades in contact while cutting. Suitable means, not shown, may be provided for driving gears 31 at the proper speed with reference to the web. Gears 31 are angularly movable on discs 40 to permit accurate positioning of blades 30 with reference to the blades 17 on cylinder 10.

Means are provided for driving the leading blades 17 on cylinder 10 slightly faster than the speed of the running web, and for this purpose (see Fig. 8) the cutting edge of the shear-cutter blades 17 on this cylinder projects slightly beyond the pitch circle of its driving gear. Means are also provided for driving the following blades 30 on cylinder 11 very slightly faster than the speed of the paper web, and this is accomplished by setting the cutting edge of the following blades 30 on the pitch circle of the gears 31 driving cylinder 11.

The speed of the web and sheet, and the speeds of the cutting edges of blades 17 and 30 in the preferred embodiment are such that, considering the angle of the cylinder axes relative to the line of web feed, the leading blade edge travels faster than the following blade edge, the following blade edge travels faster than the paper web and the cut sheet travels faster than the leading blade edge, so that the leading edge of the web, the cutting edges of blades 17 and 30 and the

trailing edge of the sheet move apart from each other immediately after cutting.

The shear cutting mechanism of the present invention may be used with many types of folding mechanisms, such as that diagrammatically illustrated in Figure 8. As there shown the folding cylinder 12 comprises a cylindrical body 45, provided with folding blades 46 which are adapted to be periodically actuated to fold off sheets from the cylinder surface. Sheet taking means 47 are provided for gripping the leading ends of the sheets as they are fed to it from the cutting mechanism and the axis of the folding cylinder is preferably positioned a full sheet length below the cutting cylinder axis, the grippers being timed to close upon and grip the leading end of the sheet immediately prior to the time any cutting of the web W starts. The cylinder surface is preferably formed on a spiral of slightly increasing diameter from each gripper 47 to the following folding blade 46, the diameter at the gripper being sufficient to produce a peripheral speed equal to that of the paper speed. The cylinder surface from the folding blade 46 to the following gripper 47 is preferably cylindrical and of sufficient diameter to produce a peripheral speed slightly in excess of web speed.

Figures 6 and 7 illustrate diagrammatically the angular relationship between the cylinder blades and web path. As shown in these figures, the web is fed vertically downward between the cutting cylinders. Figure 6 represents the right-hand cylinder, at the beginning of the cut, and cylinder 10 rotates about an axis which is displaced slightly from the horizontal. Line 50 indicates the developed projection of the blade on the web W, while line 51 indicates the line along which the web is to be cut. The blades 17 and 30 are so set that the cut begins at the high end of the cylinder and progresses towards the low end of the cylinder to produce a horizontal cut, transverse to the line of web feed.

Figure 7 is a similar view showing the parts at the end of the cutting operation, and as will be noted the blade 17 has gained very slightly on the web, and the portion of the blade first to cut the web has moved below the cut 51 and out of the way of the edge of the web immediately behind the cut.

Figure 9 of the drawings illustrates several successive positions of the shear cutting blades, together with the web, all taken in the same vertical plane, and illustrates the manner in which the blades move away from each other and from the cut edges of the web. In this figure, the leading blade 17 is shown at the right, while the following blade is shown at the left of the figure. In the position "a" of the blades, the grippers 47 on the folding cylinder are just beginning to take the lead end of the web W. At position "b", severance of the web at that section is effected and is completed when knives 17 and 30 engage each other. The blades then move through position "c" and position "d", forcing the trailing end of the sheet and the new lead end of the web apart by the overlapping of the blades.

In Figure 9, the successive positions of the trailing end of the sheet are indicated by the short double line, while the leading end of the web is indicated by the short heavy line between the two cylinders. It will be noted from a close inspection of these successive lines that the cut edges of the web and sheet are gradually moved apart perpendicularly, due to the faster travel of the sheet and the lateral pushing apart of

these edges by the blades 17 and 30. This lateral movement of the sheet end causes the sheet to clear blade 30, due to the inclination of the blade and the faster travel of the sheet, while the web end clears blade 17 due to the faster travel of the blade. Inasmuch as the lateral movement of the sheet also causes the cut edges to be moved nearer the cylinder centers, the speed of the blades is reduced relative to the paper speeds. Furthermore, after position "d", the blades are moving away from the line of web feed slowing the perpendicular travel of blades 17 and 30. In this way, the blades are constantly moved out of the way of the sheets through positions "e", "f", "g" and "h" and there is no tendency for the sheets or web to buckle, as has heretofore been the case. Due to this avoidance of buckling of the sheets, the leading end of the web has no tendency to go to one side or the other after the blades have moved apart to the position "h" and the lead end of the web is easily guided into the guides 48, which extend to a point closely adjacent to the folding cylinder 12. There is also avoided any tendency of the trailing edge of the sheet to be moved to the left by the cutting edge of the following blade 30, as has heretofore been the case, and there is no danger of the trailing end of the sheet being caught on the upper and pointed end of the left-hand guide 48.

The invention in its broader aspects is not limited to the specific mechanisms shown and described but departures may be made therefrom within the scope of the accompanying claims without departing from the principles of the invention and without sacrificing its chief advantages.

What I claim is:—

1. A folding and cutting mechanism including in combination a pair of shear cutter cylinders, and a cylinder provided with sheet grippers to take a sheet as it is cut from a web by the shear cutters, a blade on each cutter cylinder, one of said blades travelling faster than web speed, and said gripper cylinder being provided with sheet-engaging surfaces which are spiral in cross-section to accelerate the cut sheet immediately after cutting to move the sheet away from said faster blade.

2. A folding and cutting mechanism including in combination a pair of shear cutter cylinders and a cylinder provided with sheet taking means and folding blades to take a sheet cut from a web by said shear cutters, a blade on each cutter cylinder, both of said blades travelling slightly faster than web speed and one slightly faster than said other blade, and said gripper cylinder being formed with a spiral surface to accelerate the sheet immediately after cutting to move it away from the slower blade.

3. A shear cutter including in combination a pair of cylinders to rotate together, a shear cutter blade on each cylinder and means for driving the cylinders with the cutting edges of both blades travelling in excess of web speed and the cutting edge of the one blade in excess of the other.

4. A shear cutter including in combination a pair of cylinders to rotate together, a shear cutter blade on each cylinder and a gear coaxial with each of said cylinders for driving the cylinders at substantially web speed, the cutting edge of one blade lying on the pitch circle of one gear while the cutting edge of the other blade projects beyond the pitch circle of its driving gear.

5. A shear cutter including in combination a

pair of cylinders of substantially the same size to rotate together, a shear cutter blade on each cylinder and a gear coaxial with each of said cylinders for driving the cylinders at substantially web speed, the cutting edge of the leading blade being set farther from its center of rotation than the following blade edge is from its center. 5

6. A shear cutter including in combination a pair of cylinders to rotate together, a shear cutter blade on each cylinder and a gear coaxial with each of said cylinders for driving the cylinders at substantially web speed, the cutting edges of said blades being set on slightly different radii whereby one cutting edge moves slightly faster than the other and both move in excess of web speed. 10 15

7. A shear cutter including in combination a pair of cylinders to rotate together, a shear cutter blade on each cylinder and means for driving the cylinders with the cutting edges of said blades slightly in excess of web speed and with the leading blade slightly faster than the other. 20

8. A shear cutter cylinder including in combination a rotatable body having blade supporting means thereon, a blade mounted thereon and movable towards and from the axis and a pair of discs coaxial with the cylinder and at the ends of said cylinder for supporting a blade gauging member. 25

9. A shear cutter cylinder including in combination a rotatable body having blade supporting means thereon, a blade mounted thereon and movable towards and from the axis and a pair of discs coaxial with the cylinder and positioned at either end of the blade, said discs having their peripheries alined with the edge of the blade in proper position. 30

10. A shear cutter cylinder including in combination a rotatable body having blade supporting means thereon, a blade mounted thereon and movable towards and from the axis and a pair of gauge supporting members, one at either end of the blade for gauging the position of the blade. 40

11. A shear cutter cylinder including in combination a rotatable body having blade supporting means thereon, a helical blade mounted thereon, means for bending the blade toward and from the cylinder axis and a pair of discs coaxial with said cylinder, one disc at either end of the blade, for supporting a blade gauging member. 45

12. A shear cutter cylinder including in combination a rotatable body having blade supporting means thereon, a helical blade mounted thereon, means for bending the blade toward and from the cylinder axis and a pair of discs coaxial with said cylinder, one disc at either end of the blade, said discs being of equal diameter and corresponding to the radius of the helical blade, whereby a straight edge laid across said discs will contact with the blade edge when properly positioned. 50 55

13. The method of cutting sheets from a moving web including moving the web at a uniform rate, shearing said web progressively across said web at right angles thereto by means of shear cutter blades moving with the web and having the leading blade moving faster than the following blade and accelerating said sheet during cutting to remove it from the cutting means as the leading blade is moved away from the lead end of the web. 60 65

14. A shear cutter mechanism for folding machines including in combination a pair of rotatable supports and substantially helical blades on said supports in shearing relation, each portion of the cutting face of one blade being non-radial with respect to its support, while the cutting face of the other blade lies on an ex- 70 75

tension of said first cutting face in shearing relation.

15. A shear cutter mechanism for folding machines including in combination a pair of rotatable supports and blades on said supports in shearing relation, each portion of the cutting face of one blade being non-radial with respect to its support, while each portion of the cutting face of the other blade lies on an extension of said first cutting face

10 as they come into shearing relation.

16. A shear cutter mechanism for folding machines including in combination a pair of rotatable supports and substantially helical blades on said supports in shearing relation, each portion of the cutting face of one blade being non-radial with respect to its support, and each portion of the cutting face of the other blade being

15 radial with respect to its support.

17. A shear cutter mechanism for folding machines including in combination a pair of rotatable supports and substantially helical blades on said supports in shearing relation, each portion of the cutting face of the following blade being 5 rearwardly inclined with respect to the radius of its support, and the corresponding portion of the leading blade lying on the extension of said face while in shearing relation.

18. In a shear cutter, a support for a removable 10 blade, a blade, and means for mounting the blade on said support including a member threaded into said support and bearing against one face of said blade, a second threaded member coaxial with said first member and clamping said blade to said 15 first member.

CURTIS S. CRAFTS.
